ABSTRACT

A return mechanism for a watch having two hands comprises a pivoted lever acting on two heart cams, one for one watch hand and the other for another watch hand. The return lever is pivoted on a support by an eccentric pivot pin which is frictionally mounted on the support so that it can be rotated to change the pivot axis of the return lever relative to the two cams and thereby return both hands precisely to zero position.

FIG.1

FIG.2

FIG.3

ADJUSTABLE RETURN MECHANISM FOR A WATCH

The present invention relates to a return mechanism for a stop watch or chronograph.

In a watch having two return parts, for example a minute hand and a second hand, operated by a single return button, a heart cam for the minute hand and a second heart cam for the second hand are engaged by a single return lever to return the hands to zero position. However because of manufacturing error of the component parts, the return lever may engage the two cams unequally so that when it is stopped by engagement with one cam there is still a gap between the return lever and the other cam. This causes indicating error in the zero positions of the hands. In order to correct this, it has heretofore been the practice to file off the "high" cam so that the lever will engage both cams equally in zero position. However the filing of the cam results in a rough face so that the coefficient of friction is increased and the operation of the return mechanism is thereby impaired. Moreover the angle of the flat face of the cam engaged by the return lever may be altered in the filing operation so that the corresponding hand is not returned accurately to zero position. Correct filing of the cam requires considerable skill and time thereby increasing the cost of manufacture of the watch.

It is an object of the present invention to provide for convenient adjustment of the resetting mechanism of a stop watch or chronograph to correct for manufacturing errors in a simple, quick and convenient manner without increasing the number of parts and thereby the cost of the watch.

The object and advantages of the invention will be more fully understood from the following description of preferred embodiments of the invention shown by way of example in the accompanying drawings in which

FIG. 1 is a schematic plan view of the return mechanism of a watch

FIG. 2 is an enlarged cross section taken approximately on a line 202 in FIG. 1, and

FIG. 3 is a schematic plan view showing a modification.

In the embodiment illustrated in FIGS. 1 and 2, the inner end of the stem of a manually operable return button 1 engages an arm of a return lever 2 which is pivotally mounted by means of a pivot pin 3 on a support plate 4. The pivot pin 3 is a frictionally rotatable eccentric pin having a pivot shaft portion 3a fitting frictionally into a hole 4a in the support plate 4 and an eccentric portion 3b about which the return lever 2 operates and which accordingly defines the pivot axis of the lever. The eccentric pivot pin 3 is adjustably rotatable by means of a screw driver or other instrument inserted in a slot 3c provided in the end face of the eccentric portion 3b. The pivot pin is frictionally held in the position to which it is rotated.

The return lever 2 has a flat face 2a engaging a heart cam 5 for the second hand of the watch and a flat face 2b engaging a heart cam 6 for the minute hand. It will be seen that the heart cams 5 and 6 are spaced apart from one another and thus at different distances from the pivot axis of the return lever 2. Moreover the cam-engaging face 2a of the return lever is at a different angle than the face 2b engaging the cam 6 with respect to the pivot of the lever. A return spring 7 engages an arm of the return lever 2 so as to return the lever and hence the button 1 to normal or rest position.

The eccentric pivot pin 3 provides means for quickly and accurately adjusting the return lever 2 so as to engage both of the heart cams 5 and 6 equally and thereby bring the respective watch hands simultaneously and precisely to zero position. If, when the return lever 2 is fully engaged with the heart cam 5, there is still play between the lever and the flat face of the heart cam 6, the eccentric pivot pin 3 is rotated so as to raise the pivot axis as viewed in FIG. 1 and thereby bring the face 2b of lever 2 into firm engagement with the flat face of the cam 6. Conversely if there is a gap between the lever 2 and the heart cam 5 when the lever is in full engagement with the heart cam 6, the eccentric pivot pin 3 is rotated so as to lower the pivot axis as viewed in FIG. 1. Moreover by reason of the different angles as which the faces 2a and 2b of the lever 2 are disposed it will be seen that lateral movement of the pivot axis of the return lever 2 as viewed in FIG. 1 will produce more change with respect to cam 6 than with respect to cam 5. This provides a further means for adjustment of the engagement of the return lever 2 with the heart cams 5 and 6 by selective rotation of the eccentric pivot pin 3.

In the modification illustrated in FIG. 3 the return lever is in effect divided into two parts, namely a main lever 12 which is mounted on the support plate 4 by a frictionally rotatable eccentric pivot pin 3 and an auxiliary return lever 13 mounted on the support plate 4 by a pivot pin 14. The auxiliary lever 13 has a flat face 13a engageable with a heart cam 5 for the second hand of the watch. The main return lever 12 has a portion 12a engageable with the auxiliary cam 13 to actuate the heart cam 5 and a flat face 12b engageable with the heart cam 6. A return spring 17 acts on the auxiliary lever 13 to return to lever 13, the main return lever 12 and the return button 1 to normal or rest position.

The return mechanism illustrated in FIG. 3 operates in the same manner as that of FIGS. 1 and 2 except that the return lever 12, instead of acting directly on the heart cam 5, acts through the auxiliary lever 13. As in the embodiments of FIGS. 1 and 2, the pivot axis of the main return lever 12 is adjustable both vertically and laterally as viewed in FIG. 3 by the eccentric pivot pin 3 so that both heart cams 5 and 6 are fully engaged simultaneously so as to bring the corresponding hands precisely to zero position.

If the watch has more than two return parts as shown, the return mechanism in accordance with the present invention can be applied to any two of them so as to provide convenient and accurate adjustment.

As will be seen from the foregoing description, the eccentric pin serves both as an adjusting means and as the rotary axis of the return lever so that the number of parts of the mechanism is not increased by providing extra parts for adjustment. The adjustment of the mechanism can be effected quickly, easily and accurately by the single operation of rotating the eccentric pivot pin of the return lever. Moreover the adjustment is continuous rather than step-wise so that microadjustment is possible. If it is found that an over-adjustment has been made, this can be quickly and easily corrected merely by rotating the eccentric pivot pin of the return lever in the opposite direction. Such facile correction of over-adjustment was not possible with the prior art method of filing one of the heart cams. It will thus be seen that the invention represents an important advance in the art.

While preferred embodiments of the invention have been illustrated in the drawings and are herein particularly described, it will be understood that the invention is in no way restricted to these embodiments and in particular the arrangement and location of the heart cams can be varied provided only that adjustment of the pivot axis of the return lever has a different effect with respect to one heart than with respect to another.

What I claim and desire to secure by Letters Patent is:

1. A return mechanism for a watch having two operating members, comprising a support, a manually operable return lever, means for pivotally mounting said return lever on said support, first cam means operable by said return lever for returning one operating member to starting position, second cam means operable by said return lever for returning another operating member to starting position, said first and second cam means being located at different distances from said pivot means, said pivot means comprising an eccentric pivot pin mounted on said support for rotation to change the pivot axis of said return lever relative to said cam means and thereby adjust said return lever

to return both of said operating members precisely to starting position, said eccentric pin being frictionally held in adjusted position.

2. A return mechanism according to claim 1, in which said return lever has two faces at different distances from said pivot pin respectively engaging said first and second cam means.

3. A return mechanism according to claim 2, in which said faces are flat and are disposed at different angles relative to a line connecting each said face to the pivot axis of said return lever.

4. A return mechanism according to claim 1, in which an auxiliary return lever pivotally mounted on said support has a face engaging one of said cam means and said return lever has a face engaging the other of said cam means and a portion engaging said auxiliary return lever.

5. A return mechanism according to claim 4, in which a return spring acts on said auxiliary return lever to return both said first-mentioned return lever and said auxiliary return lever to rest position.

UNITED STATES PATENT OFFICE
CERTIFICATE OF CORRECTION

Patent No. 3,701,250

Dated October 31, 1972

Inventor(s) TSUNEYOSHI ONO

It is certified that error appears in the above-identified patent and that said Letters Patent are hereby corrected as shown below:

In the heading of the printed patent item "[73]" after "ASSIGNEE" cancel "Xerox Corporation, Stamford, Conn." and insert --KABUSHIKI KAISHA SUWA SEIKOSHA, a Japanese Company, Tokyo, Japan.--

Signed and sealed this 12th day of February 1974.
